ENCLOSURE FOR A STEREOGRAPHIC
RECORD PLAYER

Arthur K. Tateishi, 40 Belvia Road,
Toronto, Ontario, Canada

Filed Mar. 20, 1968, Ser. No. 11,069

Term of patent 14 years

(Cl. D56—4)

FIG. 1

FIG. 2

FIG. 3

FIG. 4

FIG. 5

FIG. 6

FIG. 7

FIG. 1 is an elevational front view showing a stereophonic record player according to my design in playing position;

FIG. 2 is a plan view of FIG. 1;

FIG. 3 is an elevational rear view of FIG. 1;

FIG. 4 is a bottom view of FIG. 1;

FIG. 5 is an elevational left hand side view of FIG. 1;
FIG. 6 is an elevational right hand side view of FIG. 1;
and

FIG. 7 is an elevational front view showing the stereophonic record player according to my design in closed position.

The dominant features of my new design are shown in solid lines in the drawing.

I claim:

The ornamental design for an enclosure for a stereophonic record player, as shown and described.
